UNITED STATES PATENT OFFICE.

JOSEPH H. DICKINSON, OF CRANFORD, NEW JERSEY.

PLAYER-PIANO.

1,028,996.

Specification of Letters Patent. Patented June 11, 1912.

Application filed March 14, 1912. Serial No. 883,663.

To all whom it may concern:

Be it known that I, JOSEPH HUNTER DICKINSON, a citizen of the United States, and a resident of Cranford, in the county of Union and State of New Jersey, have invented certain new and useful Improvements in Player-Pianos, of which the following is a specification.

This invention relates to improvements in player pianos and particularly to devices for automatically controlling the actuation and operation of certain parts of the piano player mechanism.

The object of my invention is to provide a new and improved device of this kind which automatically, by means of the perforated music sheet, successively or suddenly moves certain elements of the player mechanism in one direction or the reverse thereof, which device is simple in construction, effective and reliable in action.

In the accompanying drawings in which like letters of reference indicate like parts in all the figures, one embodiment of my invention is shown, and in these drawings Figure 1 is a diagrammatic view of my improved attachment, parts being shown in elevation, parts being broken away and others shown in section. Fig. 2 is an enlarged detail cross sectional view through the controlling valve mechanism. Fig. 3 is an enlarged detail view of parts. Fig. 4 is a face view of the part of the music sheet of its spools, parts being broken away to show the tracker.

The box or casing 1 is provided with a neck 2 which by means of a suitable tube or duct is to be connected with an air rarefying device, such as is common and well known in player pianos. The chamber 3 formed in said box or casing 1 is provided with a neck 4 from which a tube or conduit is to extend to the wind-chest of a piano player action in any well known manner.

A duct or passage 5 in said box is in communication with the neck 2 and can be closed more or less by a valve 6 pivoted at 7 to an arm 8 of a rock shaft 9 in said box or casing 1 and said valve 6 is connected by a pivoted link 10 with the movable board 11 of a bellows 12 provided with a spring 13 for expanding it and the interior of this bellows communicates with the chamber 3 in the bottom of the box 1.

Outside of the box 1 the shaft 9 is provided with an arm 14 connected by a con-

necting rod 15 with a sliding bar 16 suitably guided, for example, by lugs 17, so that it can be moved lengthwise in either direction. A friction plate 18 bears on the face of the bar 16 for the purpose of holding it at rest at whatever position it may have when action thereon stops. On one edge of said bar 16 two racks 19 and 20 are formed, the teeth of the same extending in opposite directions. 65 These teeth can be engaged by two pawls 23 mounted on the movable boards of pneumatics 21 and 22. As these pneumatics are alike I will describe only one.

To the movable board of the pneumatic 21 the pawl lever 23 is pivoted at 24 and is provided with a toe 25 on which a spring 26 acts for the purpose of throwing the pawl upward or outward to such extent that it can engage the teeth of the rack 19 on the bar 16. An adjustable stop 27 here shown in the form of a screw in the fixed board of the bellows serves for controlling the distance of the throw of said movable board of said pneumatic or bellows. When the pneumatic 21 is fully expanded by its spring 28 an upwardly projecting toe 29 of the pawl 23 comes in contact with the fixed pin 30, whereby the spring 26 is more or less compressed and the free end of the pawl 23 is swung down to such an extent as to clear the corresponding rack and to permit the bar 16 to be moved lengthwise without in any way engaging said pawl. The interior of the bellows 21 is connected by a duct 31 with the valve chamber 32 containing a valve 33 on the stem 34, all of conventional construction. This stem can be raised by a diaphragm 35 over a recess 36 connected by a tube 37 with a duct in the tracker 38. 95 There are four such ducts marked 39 in the tracker and with them slots 40 can register which are arranged in four longitudinal rows in the perforated music sheet 41, which is wound in conventional manner on the spools 42 and 43.

I provide two additional bellows 44 and 45, the movable boards of which have considerably larger throw than the movable boards of the bellows 21 and 22, in fact the bellows 44 and 45 are to move the bar 16 to its limit in either direction, that is as far as stops 46 and 47 would permit. For this purpose each bellows is provided on its movable board with an arm 48 which can 110 react on one end of the bar 16. Each bellows 44 and 45 is connected by a tube 49 to

a valve mechanism such as previously described and this valve mechanism is connected by a tube such as previously described with one of the tracker ducts 39. In 5 the embodiment shown the two outer tracker ducts are connected with the valve mechanism for the pneumatics 44 and 45 and the intermediate ducts 39 are connected with the valve mechanism for the bellows 21 and 22. 10 Slots 40 are cut in the music sheet in such a manner as to register with the corresponding tracker duct when the corresponding action of the mechanism is required to operate. 15 A spring 13 normally holds the valve 6 in what may be termed the open position for this valve and this is the position when the pumping apparatus of the player is not in operation. As soon as the pumping 20 mechanism is operated, the same rarefaction of air exists in the bellows 12 as exists in the action wind-chest and thus collapses the bellows 12, more or less and as this tension varies the movable board 11 of the bellows 25 12 vibrates. This form of air controller is well known in musical instruments and need not be further described.

The valve 16 is pivoted on the arm 7 as stated and when the arm is in the position 30 shown in full lines the valve 6 is in the position for soft playing as the greater part of the duct 5 is closed by the valve. When the arms 7 and 14 are in the position shown in dotted lines the valve 6 is adjusted for 35 forte playing and the duct 5 is only closed or almost entirely closed when the bellows 12 is completely collapsed. Intermediate positions of the arms 7 and 14, that is intermediate between the positions shown in 40 full lines and the positions shown in dotted lines represents various degrees of loudness.

If at any time the arms 7 and 14 are in the positions shown in full lines and the playing is to become louder step by step 45 the bellows 21 is repeatedly and successively exhausted so as to cause its pawl 23 to engage the teeth of the rack 19 and to, step by step, move the bar 16 to the right. The bar may be moved only one or two teeth or successively by all the teeth of the rack 19, this 50 depending upon the number of slots or holes 40 successively appearing in the corresponding row in the note sheet.

Immediately after the rack bar 16 has 55 been moved the distance of one tooth of its rack 19 by the collapsing of the bellows 21 the bellows again expands and by the contact of the toe 29 and the stop pin 30 the pawl 23 is thrown out of engagement with 60 the rack, so as to leave the bar 16 free to be moved by the other pawl or by the end bellows 44 and 45. If it is desired to swing the arms 7 and 14 instantly and in one movement from the extreme position shown in 65 full lines to the extreme position shown in

dotted lines, air is exhausted from the end bellows 44 by providing a corresponding slot or hole in the corresponding row of slots 40 in the music sheet and as the bellows 44 is collapsed its arm 48 acting on the left hand end of the bar 16 moves the same to the right to the extreme limit until it is arrested by the stop 47. In a similar way the bar 16 can be moved step by step to the left or at any time and from any position can be moved the extreme distances to the left until it is stopped by the stop 46. For example, if the melody is being played in extreme piano and it is desired to gradually play louder, a number of succeeding slots 40 are arranged in the corresponding row on the note sheet so as to gradually move the arms 7 and 14 from the position shown in full lines in Fig. 1 to the position shown in dotted lines. If, however, after one or 70 two movements of the bellows 21, it is desired to play fortissimo the bellows 44 is collapsed. If then normal playing is desired the parts can be brought to normal position successively or suddenly by means of the bellows 22 or 45. The air that enters through the note slots into the tracker duct merely serves for operating the valves as the bellows 21, 22, 44 and 45 are all exhausted into the exhausting chamber 49 which by a suitable neck 50 and connection is exhausted from the ordinary exhausting mechanism of the player piano. 80

Having described my invention what I claim as new and desire to secure by Letters Patent is:—

1. In a piano playing mechanism, the combination with an adjustable element forming part of said mechanism, of a rack and pawl means for adjusting said element in one direction or the reverse thereof, step by step, and two independent mechanisms for adjusting said valve to its limit of adjustment, in one stroke, in opposite directions, a separate pneumatic device for operating each 105 separate element adjusting means, and means for controlling the pneumatic device from a perforated music sheet, substantially as set forth.

2. In a piano playing mechanism, the combination with an adjustable element forming part of said playing mechanism, a rack bar in operative connection with said element, a pneumatic, a pawl for engagement with the rack and operated from the movable board of the pneumatic, an additional pneumatic, means for shifting said rack bar lengthwise by said additional pneumatic, in the same direction as it is moved by the pawl, and independent means for governing the operation of said two pneumatics from a perforated music sheet, substantially as set forth. 115

3. In a piano playing mechanism, the combination with an adjustable element 120

- 5 forming part of said playing mechanism, of a rack bar in operative connection with said element, a pneumatic, a pawl for engagement with the rack and operated from the movable board of the pneumatic, an additional pneumatic, means for shifting said rack bar lengthwise by said additional pneumatic, in the same direction as it is moved by the pawl, a stop in the path of said bar
10 for limiting its movement, and independent means for governing the operation of said two pneumatics from a perforated music sheet, substantially as set forth.
4. In a piano playing mechanism, the
15 combination with an adjustable element forming part of said playing mechanism, of a rack bar operatively engaged with said element, stops for limiting the lengthwise movement of said rack bar in either direc-

tion when the limit of adjustment in either 20 direction of said element has been reached, two racks formed on said bar, two pneumatics, a pawl operated from the movable board of each pneumatic, for engagement with a rack, means for throwing the pawls out of engagement with the racks when said pneumatics are expanded, two additional pneumatics, and means for shifting the said rack bar lengthwise by means of said additional pneumatics, and means for independently 30 controlling the operation of the four pneumatics from a perforated music sheet, substantially as set forth.

JOSEPH H. DICKINSON.
